(57) **CLAIM**

The ornamental design for a pile guide for docks, as shown and described.

DESCRIPTION

FIG. 1 is a top perspective view of a pile guide for docks showing the new design;

FIG. 2 is a front elevation of the pile guide for docks;

FIG. 3 is a rear elevation of the pile guide for docks;

FIG. 4 is a right side elevation of the design of the pile guide for docks;

FIG. 5 is a top plan view of the pile guide for docks; and,

FIG. 6 is a bottom plan view of the pile guide for docks.

1 Claim, 6 Drawing Sheets
